UNITED STATES PATENT OFFICE.

LOUIS T. CUSHING, OF GRAY, MAINE.

DESIGN FOR A MEDICINE-TUBE.

SPECIFICATION forming part of Design No. 34,201, dated March 12, 1901.

Application filed February 14, 1901. Serial No. 47,380. Term of patent 14 years.

To all whom it may concern:

Be it known that I, LOUIS T. CUSHING, a citizen of the United States, and a resident of Gray, in the county of Cumberland and State of Maine, have invented and produced a new and original Design for a Medicine-Tube, of which the following is a full, clear, and exact description.

Reference is to be had to the accompanying drawings, forming a part of this specification, in which similar characters of reference indicate corresponding parts in all the figures.

Figure 1 is a side view of a medicine-tube, showing my design. Fig. 2 is a front view, and Fig. 3 is a rear view.

The leading feature of my design for a medicine-tube consists in a curved body portion the two ends of which converge, and a tube extending from one of the ends at an angle to the plane of the body portion.

Referring particularly to the drawings, 1 designates the body portion, the lower part of which is of enlarged diameter, the two ends converging, and from one end a tube 2 extends at right angles to the plane of the body, 25 while the other end is bell-shaped or flaring.

Having thus described my invention, I claim as new and desire to secure by Letters Patent—

The design for a medicine-tube as herein 30 shown and described.

In testimony whereof I have signed my name to this specification in the presence of two subscribing witnesses.

LOUIS T. CUSHING.

Witnesses:

FRANK L. CLARK,
EMMA M. CUSHING.
